UNITED STATES PATENT OFFICE

CHARLES B. GRAY, OF MILLBOURNE, PENNSYLVANIA

CUTTING MACHINE

Application filed June 4, 1929. Serial No. 368,217.

This invention relates to cutting machines and more particularly to machines comprising a die and a punch for punching relatively thick sheet material, one of the principal objects of the invention being to provide improvements in an apparatus of this character whereby the same is rendered economical from the standpoints of manufacture and use and capable of cutting very narrow slots and curves of small radii in the sheet material. The present invention particularly relates to improvements in and is applicable to machines for cutting sheet-form material such as those disclosed and described in Patents Nos. 1,366,790 and 1,384,696 granted to me on January 25, 1921, and July 12, 1921, respectively.

As a corollary to the foregoing, it is a further object of the present invention to provide a machine by means of which the operator may punch holes through the sheet material which are distinct and separate from each other or which overlap in such manner that the sheet material is cut away piece by piece to form an opening larger than the cross-section of the punch.

A further object of the invention is to provide a machine wherein the overlapping strokes may be delivered on a definite line or path to thereby cut a slot the width of which is equal to the thickness of the punch, the machine being so designed that the punch may take any course desired by the operator.

A still further and important object of the present invention is the provision in a machine of the character to which the aforesaid patents relate of a pilot stem or feed limiting member which is shiftable out of axial alignment with the vertical axis of the punch and die opening, the said pilot stem being of smaller cross-sectional size than said die opening, this arrangement being provided in order to prevent jamming of the machine when the punch penetrates the sheet material. I have found that when a pilot stem is employed which is of substantially the same size as the die opening, the stem is jammed against the wall of said opening by the slug which is punched out of the sheet material. Obviously when the punch passes

through the sheet material, the material in advance or immediately below the cutting edge of the punch is caused to spread out and in so doing tends to jam the feed limiting member or pilot stem against the wall of the die opening in consequence of which said feed limiting member is rendered inoperative and the operation of the machine is interrupted. I overcome this serious difficulty by reducing the diameter of the feed limiting member to a dimension less than that of the die opening and at the same time provide means permitting axial misalignment between said pilot stem and the common vertical axis of the punch and the die opening.

A further object of the present invention is the provision of means for permitting the said feed limiting member or pilot stem to be drawn downwardly and below the plane of the sheet material to be punched manually and without necessitating uncoupling of any parts of the machine.

Other objects and advantages of the invention will appear more fully hereinafter.

The invention consists substantially in the combination, construction, location and relative arrangement of parts, all as will be described more fully hereinafter, as shown in the accompanying drawings, and as finally pointed out in the appended claims.

In the accompanying drawings which show preferred forms of the invention:

Figure 1 is a side elevation constructed in accordance with and embodying the principles of the present invention;

Figure 2 is a front elevation thereof;

Figure 3 is a rear elevation thereof;

Figure 4 is a side elevation (partly in section) of the lower or pilot stem turret mechanism;

Figure 5 is a vertical sectional view taken on the line 5—5 of Figure 4;

Figure 6 is a top plan view of the mechanism shown in Figures 4 and 5;

Figure 7 is a partial horizontal sectional view taken on the line 7—7 of Figure 5;

Figure 8 is a modified construction arrangement of a pilot stem supporting structure embodying the principles of the present invention;

Figure 14 is a top plan view of the die shown in Figures 5 and 10;

15 Figure 15 is a top plan view of a modified form of die;

Figure 16 is a vertical sectional view through the die and clamping block therefor shown in Figure 15; and

20 Figure 17 is an end elevation of the die and clamping block therefor shown in Figure 16.

Referring now to the drawings, wherein is shown a machine embodying the principles of the present invention, it will be observed that body 10 of the machine includes an upper arm 11 and a lower arm 12, the body being supported upon a floor or suitable foundation by the pedestals 13. At this point attention is directed to the fact that the plane in which the sheet material to be punched lies 30 is herein termed the sheet plane of the machine.

On the outer or left hand end of the arm 12 is a horizontal seat 14 on which rests a casting 15 for supporting the die and the lower turret mechanism operatively associated therewith, all of which is designated generally by the reference numeral 16, said mechanism including a vertically reciprocable feed or pilot stem which is operable in synchronism with a vertically reciprocable punch located above the sheet plane. Suitable bolts or other securing elements are employed to secure the casting 15 upon its seat 14.

45 Figures 4, 5 and 6 show this turret mechanism most clearly and referring more particularly to these figures it will be seen that the outer end of arm 12 is provided with a vertically extending substantially cylindrical sleeve 17, the upper surface of which constitutes the horizontal seat 14 aforesaid. Disposed within the outer cylindrical sleeve 17 is the casting 15, this latter member being in the form of a vertical bearing sleeve 19 having an annular flange 20 surrounding the external surface thereof and adapted to rest upon the upper surface of the cylindrical sleeve 17. The internal surface of the sleeve 19 constitutes a vertically extending journal or bearing within which a die-supporting 50 turret 21 may be rotated in either direction by a means and for a purpose to be presently described.

60 This turret 21 is in the nature of a hollow drum arranged for rotation about a vertical axis, the upper end thereof being provided

with an annular flange 22, the lower surface of which is adapted to rest upon the upper surface of the vertical bearing sleeve 19. The lower end of the said drum projects downwardly below the lower end of said bearing sleeve to thereby provide a cylindrical surface about which a cable 23 may be wound for effecting the desired rotation of the drum or turret 21. In order to provide space for this cable 23 the internal surface of the outer cylindrical sleeve 17 is annularly recessed, as at 24. Extending rearwardly through the wall of the sleeve 17 is a divided horizontal passage or slot 25 adjacent the outer end of which a pair of vertically spaced pulleys 26 and 27 are journalled for rotation about a common vertical axis. The cable 23 passes around one of these pulleys, thence about the surface of the drum 21 and finally around the other of said pulleys, the free ends of the cable being extended rearwardly of the machine for securing, in a manner well understood in the art, to a pulley 28 which is secured to and is rotatable with a vertically disposed shaft 29. This shaft 29 is provided with a hand wheel 30 for conveniently rotating the same in either direction about a vertical axis, it being understood, of course, that by rotating the hand wheel a corresponding rotation of the turret or drum is effected within its bearing sleeve 19. Inasmuch as the turret supports the die, as will appear more fully hereinafter, this rotation of the turret makes it possible to positionally adjust the die with respect to the direction of feed of the work to be punched or cut.

65 This leads us now to a description of the mechanism for maintaining a fixed relation between the turret and the direction of feed of the sheet once the proper positional adjustment therebetween is obtained. As appears most clearly in Figures 5 and 6, the external periphery of the upper flange 22 of the turret is provided with a plurality of circumferentially arranged notches 31 any one of which is adapted for vertical alignment and registry with a vertical recess or groove 32 formed in the external surface of the bearing sleeve 19. Cooperating with this vertical recess 32 in the bearing sleeve 19 is a vertically aligned recess 33 formed in the internal surface of the outer cylindrical sleeve 17. Operatively positioned within the recess or groove 32 and arranged for sliding movement vertically therein is a key or locking dog 34 the lower end of which is receivable within the recess 33, and is provided with a reduced stem 35. Surrounding the stem 35 is a coiled compression spring 36 the lower end of which rests upon the bottom wall of recess 33, the tendency of this spring being to normally urge the locking key 34 upwardly and into interlocking engagement with any one of the circumferentially spaced notches 31 formed in the turret 21 depending 70

upon which of said notches is brought into registry with the aligned recesses 32 and 33. As appears most clearly in Figure 5, the locking key is provided with a lateral extension 5 37 to which is secured a depending stem 38 to the lower end of which a link or other suitable means (not shown) may be secured for effecting disengagement of the locking key from the turret 21 against the compressive 10 force exerted by the spring 36. A plate 39, secured to the bearing sleeve 19 by the screws 40, serves to prevent lateral displacement of the locking key during the vertical movement thereof.

15 Provided in the upper surface of the turret 21 is a substantially rectangularly shaped depression or seat 41 within which the die is disposed. Figures 4, 5, 6, 10, 11 and 14 show one form of die which may be employed in 20 conjunction with the herein described machine, while Figures 8, 15, 16 and 17 show a modified form of die. In Figures 4, 5, 6, 10, 11 and 14 the die comprises a plurality of cutting elements 42, 43 and 44 all of which are 25 securely clamped together by wedging blocks 45-45 to which pressure is applied laterally by means of screws 46. The intermediate cutting element 44 is adjustable longitudinally of the laterally disposed cutting elements 42 and 43 this adjustment being effected by the screw 47 prior to clamping said elements together in the manner and by the means just described. It will be observed 30 that the proximate faces of the cutting elements are so tapered with relation to each other as to provide discharge relief below the cutting edges in the upper surfaces thereof, it being further observed that the die so formed is provided with no cutting edge or 35 other obstruction opposite the cutting edge of the intermediate cutting element 44. In other words, a die is provided having three cutting edges, two of which are substantially parallel to each other and the other of which 40 extends at right angles thereto. In order to effectually preclude vertical dislodgment of the wedging blocks 45-45, the outer surfaces thereof with which the screws 46 engage are tapered, as at 48. (See Figure 4.)

45 In the modified form of die as shown in Figures 15, 16 and 17, the die proper, designated 49, is of circular form and is clamped in position within a holding block 50 therefor, this block being kerfed or split, as at 51, 50 to permit the opposite sides thereof to be forced into die clamping position by means of the screws 46. In this circular form of die there is, of course, no adjustment of the cutting edge, different sized dies being employed for different sized punches. As in the arrangement shown in Figure 14, the holding block 50 for the circular die may be adjusted longitudinally by means of a screw 55 similar to the screw 47.

55 Suitably supported within the bore of the

turret 21, as by means of an integrally formed spider 52 or the like, is a tubular sleeve 53, the axis of which is coincident with that of the turret. Secured to the bottom of this sleeve 53, preferably by the screws 54, 70 is a centrally apertured plate 55 having an axially extending flange 56 projecting interiorly of the sleeve 53. Telescopically received within and arranged for reciprocating movement with respect to said tubular sleeve is an internal shell 57, the upper end 58 of which extends vertically beyond the corresponding end of the tubular sleeve 53 and is of substantially frusto-conical shape. The upper wall of said frusto-conical portion of the internal shell 57 is centrally apertured, as at 59, and is provided with a depression 60 formed by a vertically projecting annular flange 61 having a relatively sharp upper edge. Preferably, the base of the frusto-conical portion 58 is provided with a depending annular flange 62 freely embracing the upper end of the tubular sleeve 53, the function of this flange 62 being to serve as an effective apron to prevent the ingress of dirt, 80 grit and the like between the sliding surfaces of the members 53 and 57.

85 Disposed immediately above the top wall of the internal shell 57 is a member 63 of substantially conical shape, said member 63 being provided with a stem 64 projected downwardly through the aperture 59 in said top wall of the shell 57. As appears most clearly in Figure 5 the base of the conical member 63 is provided with an annular groove 65 within which the axially projecting flange 61 of the shell 57 is received. It will be understood that the groove 65 is wider than said flange 61 and that the sharp upper edge of the latter engages the top wall 100 of said groove. The lower end of the downwardly projecting stem 64 of the member 63 is provided with an annular abutment, preferably in the form of a nut 66 threaded thereon, a compression spring 67, surrounding said stem 64, being interposed between said abutment and the top wall of the shell 57. It will be apparent that the spring 67 serves to draw the conical member 63 downwardly and into seating engagement with the 105 top surface of the shell 57. Under normal conditions, when the member 63 is properly seated upon the shell 57 the vertical axis of said member is and should be coincident with that of said shell.

110 Carried by and projecting vertically above the conical member 63 is the feed or pilot stem 68, it being observed that said stem is coaxial with the turret 21 when the member 63 is properly seated upon the shell 57. The stem 68 is immovably secured to the member 63 by a suitable key or set screw 69. It is important to note at this point that the upper and effective portion of the pilot stem is of 115 smaller cross-sectional area than the die 120

125

opening so that under certain operating conditions the stem may be shifted out of its normally true vertical position without jamming against the side wall of the die opening 15 through the force occasioned by the spreading action of the punched out slug. This axial misalignment of the pilot stem with respect to the concentrically arranged turret 21 and tubular shell 57 is permitted by means 20 of the construction just described, it being apparent that upon the application of a laterally directed force against the upper end of the pilot stem the conical member 63 will be caused to rock upon the tubular shell 57, the portion of the sharp edged flange 61 which is diametrically opposed to the side at which said force is directed being constituted 25 a fulcrum about which the conical member 63 is adapted to rock. This rocking movement of the conical member relative to the tubular shell 57 is of course resisted by the compression spring 67 with the result that when said force which causes the pilot stem to be shifted out of its true vertical position 30 is withdrawn the spring 67 immediately draws the conical member 63, and accordingly the pilot stem, into correct position.

The mechanism for effecting reciprocation of the pilot stem will now be described. As 35 appears most clearly in Fig. 5 the tubular shell 57 is interiorly threaded, as at 69, for reception of the upper threaded end of a vertically extending rod 70, which latter is projected downwardly through the apertured bottom plate 55 of the internal sleeve 53. The lower end of this rod 70 is adapted to have secured thereto a link or the like connected to a foot treadle (not shown) by means of which the said rod may be manually depressed. A compression spring 71, interposed between the axial flange 56 on the bottom plate and the upper threaded portion of the rod 70, tends normally to urge the shell 57 upwardly so that the upper end of the 40 pilot stem 68 which is operatively associated with said shell is projected vertically above the sheet plane.

Adjustably secured to the threaded rod 70 and extending longitudinally thereof is an 45 arm 72, the lower end of which is provided with a laterally projecting pin or stud 73. Suitably journalled in bearings arranged at opposite ends of the lower arm 12 of the machine is a rearwardly extending horizontal shaft 74 upon the forward end of which is keyed a bell crank lever 75. The branch 76 of this lever extends laterally of the shaft 74 and toward the turret mechanism described above so that the branch 77 thereof, which is 50 provided with an elongated slot 78, lies flat against the arm 72 with the pin 73 projecting into said elongated slot 78. Under normal conditions and due to the compressive force exerted by the spring 71 against the tubular shell 57 the threaded rod 70 is raised 55

such that the pin 73 engages the top of the bell crank lever slot 78, it being then apparent that by depressing the lever 75 the rod will be lowered. Due to the action of spring 71 as aforesaid when the lever is 60 raised the rod will also rise in unison with the lever. Should it be desired, however, to lower the rod 70 without moving the bell crank lever it is merely necessary to depress the foot treadle (not shown) in consequence 65 of which the said rod will be drawn downwardly against the action of the spring 71, the extent of such downward movement being determined by the length of the slot 78 in the branch 77 of the lever, it being understood that in this manual operation of the rod the pin 73 rides freely in said slot 78.

In Figure 8 a somewhat modified arrangement is shown for permitting axial misalignment of the pilot stem to take place with respect to the true vertical axis in order to prevent the upper end thereof from jamming between the slug being punched out and the internal wall of the die when the punch is depressed. In said modified arrangement the turret 21 is provided interiorly thereof with a vertically extending coaxial sleeve 79 to the bottom end of which is secured, preferably by screws 80, an apertured plate 81. Slidably disposed within the vertical bore of the sleeve 79 is a plunger member 82 from the upper end of which projects the vertically extending pilot or feed stem 83. Depending from the bottom end of the plunger and projecting downwardly through the apertured plate 81 is a rod 84 to the lower end of which the bell crank lever 75 is connected in the same manner as described in connection with the construction shown in Figure 5. A compression spring 85 embraces the upper portion of rod 84 and is interposed between the plate 81 and the bottom of the plunger 82, this spring being operative to force the plunger and the pilot stem carried thereby upwardly. The die which is secured upon the upper surface of the turret is of the type shown in Figures 15, 16 and 17, it being observed that the die opening is of a cross-sectional area greater than that of the pilot stem 83. The pilot stem 83 is considerably longer than the pilot stem shown in Figure 5 and therefore has a certain degree of flexibility. It will thus appear that when a force is applied laterally against the upper end of this stem 83 the latter will bend in the direction of this force, but due to the fact that the die opening is of greater dimension than the stem there is no possibility for the stem to be jammed against the internal wall of the die through the spreading action of the slug while being punched out of the stock and so interrupt the operation of the machine. When the laterally directed force is removed the pilot stem 83, due entirely to its inherent resiliency, will return to its normal position 130

such that the axis thereof again becomes approximately coincident with that of the sleeve 79.

Figures 10, 11 and 12 relate to the upper 5 or punch turret mechanism and referring more particularly to these figures it will be observed that this mechanism is supported upon the upper arm 11 of the machine with the operating axis of the punch 85 in approximate vertical alignment with that of the pilot stem operatively associated with the lower turret mechanism. As appears most clearly in Figure 11 the upper turret or drum 86 is suitably journaled within a bearing or 10 support therefor comprising a pair of complementary bearing blocks 87 and 88 which are adapted to be secured together in embracing relation with respect to said turret by means of the bolts 89. The bearing block 20 87 is preferably formed integrally upon the arm 11 while the block 88 (see Figure 12) is detachable therefrom to facilitate assembly of the turret and associated mechanisms. It is preferable to provide wear take-up shims 25 90 in the internal surface of the removable block 88, these shims being forced inwardly into more intimate contact with the external surface of the turret 86 by means of the laterally projecting adjusting screws 91.

30 As in the case of the lower turret or drum this upper turret 86 has a cable 92 wound about the external surface of the lower portion thereof. This cable suitably passes over the vertically spaced pulleys 93 and 94 and thence over a pulley 95 which is fixed to the rear pulley shaft 29 for rotation in unison with the pulley 28. It will thus be apparent that by rotating the hand wheel 30 (see Figure 1) the upper and lower turrets may be rotated in unison and in either direction to effect the desired positional adjustment of the punch and pilot stem with respect to the direction of feed of the sheet material.

45 The upper end of the punch turret 86 is flanged, as at 95, and is provided with a plurality of circumferentially spaced notches 96 in the external surface thereof. A locking dog 97 is pivotally secured, as at 98, to the bearing block 88 and is provided with an inwardly directed portion 99 adapted for interlocking engagement with any one of the notches 96. A compression spring 100 serves 50 to maintain the dog 97 in turret locking position while a handle 101 is provided to effect disengagement of said dog from the turret. In this connection it is pointed out that the punch turret and the pilot stem turret may be 55 rotated into the desired adjusted positions independently of each other and by any suitable means other than the cables shown. It will also be understood that any suitable means may be employed to maintain the locking dogs 97 and 34 in inoperative position,

that is, out of engagement with their respective turrets.

Arranged within the internal vertically extending bore of the turret 86 and adapted for vertical reciprocatory movement therein is a 70 punch ram 102. This ram is of somewhat smaller diameter than the internal diameter of the turret, the annular space thus afforded between said ram and said turret having inserted therein a plurality of split tubular bearing members 103 and 104 arranged in longitudinal extension of each other. The external surface of the lower bearing member 104 is tapered and the lower portion of the turret 86 is correspondingly tapered to accommodate the same. The upper bearing member 103 is also tapered in its external surface, a tapered cylindrical wedge 105 being inserted between said upper bearing member and the upper internal surface of the turret. An exteriorly threaded ring 106 is threaded within the top of the turret member for forcing the cylindrical wedge downwardly into the position shown. The lower end of the ram 102 is exteriorly 75 threaded, as at 107, for receiving a substantially cup shaped member 108, the bottom wall of the latter being centrally apertured. Projecting upwardly and vertically through the ram 102 is a stem 109. Coaxial with and keyed to this stem, as at 110, is a downwardly projecting punch 85, the body of which projects freely through the apertured cup shaped member 108. It will be observed that the lower end of the bore of the ram 102 is flared to provide a substantially conical seat 111 for receiving a split cone bushing 112 having an extension projecting axially through the bottom aperture in said cup shaped member 108. It will be seen that upon threading said member 108 upon the lower end of the ram the split cone bushing will be forced into its conical seat 111 and at the same time firmly clamp 80 the body of the punch 85. Strippers 113 are operatively associated with the punch to strip the sheet material therefrom when the punch is raised. As most clearly appears in Figure 11 each of these strippers is provided with a threaded shank adapted to be threaded upwardly and into the turret member 86. Set 105 screws 114 maintain these strippers in operative position, it being understood that when said set screws are loosened the strippers may be rotated about the vertical axes of the threaded shanks thereof into a position 110 wherein the lower ends thereof are swung outwardly and away from the punch 85 and the parts immediately associated therewith. In this connection it will be noted that the strippers are vertically adjustable independently of each other so that the lower end of one may be disposed in a plane spaced above that of the other. By reason of this arrangement it becomes possible to adjust one stripper for engagement with the material to be 115 120 125 130

punched and the other stripper for engagement with the template such as is shown in Figure 8, thus precluding tilting of the sheet material when the punch is withdrawn therefrom.

The stem 109 is threaded throughout the major upper portion thereof and serves as the means for transmitting reciprocating motion to the ram 102. This reciprocating motion is initially imparted to the stem 109 by means of an eccentric 115 which is secured to and rotatable with a rearwardly extending shaft 116. Rotation is imparted to this shaft 116 in any suitable manner. Operatively associated with the eccentric 115 is a sliding block 117 which transmits a vertical reciprocating movement to a cross head designated generally by the reference numeral 118. This cross head 118 overlies and is spaced vertically above the punch turret 86, the central portion of said cross head being provided with a substantially rectangular shaped opening. Extending forwardly of the cross head and formed integrally therewith is a projection 119 having an opening 120 extending therethrough and communicating with the central opening of the cross head proper. Projecting downwardly from the forwardly projecting portion 119 of the vertically reciprocable cross head is a pin or stud 121 the purpose of which will be presently explained. Slidably disposed within the central opening of the cross head is a member 122 of a cross-section corresponding to that of said opening. This member 122 is provided with a reduced upper portion, the lateral faces of which parallel each other and the front face of which extends at right angles to said lateral faces. This member 122 is provided with a vertically extending interiorly threaded bore through which the stem 109 is threaded. A nut 123 threaded upon this stem immediately above the member 122 serves to adjustably lock said stem within said member 122. A washer 124 is preferably disposed between said nut 123 and the top surface of the member 122.

Slidably received within the lateral projecting opening 120 formed in the cross head projection 119 is a substantially flat horizontally disposed yoke 125, the legs of which are presented rearwardly and embrace the opposed lateral faces of the reduced portion of the member 122. A stem 126 is threadedly secured to this yoke and extends outwardly through the forward end of the laterally extending passage 120. The outer extremity of this forwardly extending stem 126 is provided with a pair of longitudinally spaced laterally extending pins 127. It will be apparent that when the stem 126 is thrust inwardly and toward the stem 109 the yoke 125 will operate to lock the member 122 against relative movement with respect to the cross head 118 with the result that the stem 109 is also

locked to said cross head for vertical reciprocable movement therewith.

Pivottally supported upon a suitable bearing 128 is a horizontally disposed lever 129, the free end of which terminates approximately in a line extended vertically above the punch turret locking dog 97. The rear end of the lever 129 projects somewhat beyond its pivotal support 128 and is interconnected with the frame of the machine by a coiled tension spring 130, the action of this spring being normally to urge the forward end of the lever upwardly. The lever 129 intermediate the pivotal support therefor and the forward end thereof is provided with an enlargement 131 which is apertured to permit the vertical projection therethrough of the upper end of the stem 109. At a point below the lever 129 the said stem 109 has secured thereto a collar or other such abutment 132 and upon the upper surface of which the lever 129 is adapted to rest. A compression spring 133 embraces the stem 109 along the portion thereof which extends beyond the top surface of the cross head 118 and said abutment 132. This abutment is preferably adjustable longitudinally of the stem. It will be observed that the compression spring 133 urges the stem 109 and the member 122 threadedly secured thereto upwardly through the central opening in the cross head, this upward movement of said stem and member being prevented, however, when the yoke 125 is moved into the position shown in Figure 11 by means of the laterally extending pins 127 on the yoke manipulating stem 126.

In order to effect disengagement of this yoke from the member 122, which latter is in turn threadedly secured to the stem 109, the rod 134 is shifted forwardly of the machine whereby to draw the yoke 125 out of engagement with the member 122. At the same time the rod 134 may be pulled downwardly against the action of the spring 130 to thereby depress the stem 109 independently of the eccentric 115, the cross head 118 in this instance being freed from the member 122 which is carried by said stem 109.

It will, of course, be understood that when the stem is depressed, either by the eccentric 115 or by the manually operated lever 129, the ram 102 which carries the punch 85 is also depressed, said punch being depressed below the sheet plane. In order to preclude angular displacement of the stem 109 and the ram 102 about the vertical axis of reciprocation of the punch, the ram is provided with a laterally projecting arm 136, the free end of which is forked, as at 137, to freely embrace the depending stem 121 carried by the forwardly projecting portion 119 of the cross head. A nut 138 serves to clamp the laterally extending arm 136 against the top surface of the ram.

As appears most clearly in Figure 11 the

stem 109 is made up of a plurality of vertically aligned sections, the adjoining ends of these sections being keyed together as designated by the reference numerals 139 and 140.

It will be understood, of course, that the punch 85 and the feed or pilot stem 68 are operated synchronously with respect to each other, any suitable means being employed to effect such operation. I prefer to accomplish this by mounting an eccentric 141 upon the rear end of the shaft 116 which eccentric is operable through a suitable link 142 and a crank 143 to impart an oscillatory movement 15 to the shaft 74 to the forward end of which the bell crank lever 75 of the pilot stem mechanism is secured. By properly adjusting the various levers and eccentrics hereinbefore mentioned and described it becomes a 20 simple proposition to insure synchronous operation of the punch 85 and the pilot stem 68. It is preferable to so adjust the machine that a slight space is maintained at all times between the proximate ends of the punch 85 25 and the pilot stem 68, this space being maintained constant throughout the reciprocating movement of these members.

Figure 8 generally shows the relation between the die 50, the pilot stem 83, the punch 85 and the sheet material S upon which the machine is operating. If desired a templet T may be employed to guide the punch along any predetermined line. It will be understood that when the punch is depressed 30 into the position shown in Figure 8, the material lying in advance of the punch stock will be caused to spread out or to flow in such manner that the pilot stem will be forced toward that portion of the die opening wall 35 which is opposed to the cutting edge of the punch. Due to the fact that the pilot stem of Figure 8 is of less cross-sectional dimension than the die opening, a considerable misalignment between said pilot stem and the vertical axis of the punch and die opening 40 may take place without causing the upper end of the pilot to be jammed tightly against the die opening wall. When the slug is entirely punched out of the sheet material and 45 drops through the die opening between the wall thereof and the pilot stem, the latter will of its own resiliency spring back into its normal position, that is into vertical alignment with the vertical axis of the punch 50 and die opening. What has been said with reference to the construction shown in Figure 8 is equally true of the construction shown in Figure 5, the sole difference being that in this latter construction the pilot stem or 55 feed limiting member is not inherently resilient nor is it of such great length as the pilot stem shown in Figure 8. In Figure 5 axial misalignment between the pilot stem and the vertical axis of the punch is permitted by reason of the relative movement 60

of the conically shaped pilot stem supporting member 63 with respect to the tubular shell 57, all as has been described more fully hereinbefore.

In connection with the construction shown in Figure 5, attention is directed to the fact that radial adjustment between the turret 21 and the cylindrical sleeve 17 is effected through the provision of enlarged openings 144 in the flange 20 of the sleeve 19 through which the bolts 145 are projected for threaded engagement with said cylindrical sleeve 17. This radial adjustment between the turret member and the cylindrical sleeve is desirable in order to not only effect true vertical alignment between the pilot stem 68 and the punch 85 but also to obtain a closer adjustment of the die with respect to the punch. This radial adjustment between the turret 21 and the cylindrical sleeve 17 in connection with the adjustment obtainable through the screws 46 and 47 (see Figures 14 and 15) makes possible what is in effect a vernier adjustment between the die and punch. 85

It will be understood that the invention as described and shown herein is susceptible of various changes and modifications without departing from the real spirit or principles of the invention, and it is accordingly 90 intended to claim the invention broadly, as well as specifically, as indicated by the appended claims.

What is claimed as new and useful is:—

1. In a machine for cutting sheet-form material, in combination, a die located at one side of the sheet plane, a punch located at the opposite side of said plane, a feed-limiting member located upon the same side of said plane as said die and movable through the latter and across said plane, means for synchronously reciprocating said punch and member while the latter is maintained in axially spaced relation, manually operable means for axially shifting said feed-limiting member with respect to said punch, and spring means for returning said member into operative association relatively to said punch. 100

2. In a machine for cutting sheet-form material, in combination, a die supporting turret located below the sheet plane, a punch supporting turret located above the sheet plane, a feed-limiting member operatively associated with the die supporting turret, and means for rotating said turrets about a common vertical axis whereby to angularly position said punch, die and feed-limiting member with respect to the direction of feed of the sheet material. 115

3. In a machine for cutting sheet-form material, in combination, a die supporting turret located below the sheet plane, a punch supporting turret located above the sheet plane, a feed-limiting member operatively 120

- associated with the die supporting turret, means for synchronously reciprocating said punch, and feed-limiting member along the vertical axis of said die, means for rotating 5 said turrets about said axis whereby to positionally adjust said punch, die and feed-limiting member with respect to the direction of feed of the sheet material, and means individually associated with each of said 10 turrets for locking the same in said adjusted positions.
4. In a machine for cutting sheet-form material, a turret located to one side of the sheet plane, a punch ram reciprocable along 15 the axis of said turret, means for imparting reciprocation to said punch ram, and means for axially shifting said punch ram independently of said reciprocating means therefor.
- 20 5. In a machine for cutting sheet-form material, a turret located to one side of the sheet plane, a punch operatively associated therewith, a ram movable axially through said turret and upon which said punch is supported, a reciprocable cross-head, and 25 slidable means for releasably connecting said cross-head and ram.
- 30 6. In a machine for cutting sheet-form material, a turret located to one side of the sheet plane, a punch arranged for reciprocation axially of said turret, a cross-head reciprocable toward and away from said turret, said punch being provided with an operating stem projecting freely through said 35 cross-head, and laterally shiftable means for releasably interlocking said stem with said cross-head whereby to impart the reciprocatory movement of the latter to said punch.
- 40 7. A machine for cutting sheet-form material according to claim 6 characterized in that the operating stem for said punch is constructed of detachable sections secured together in axial alignment.
- 45 8. In a machine for cutting sheet-form material, a reciprocatory punch, a supporting structure therefor, and a pair of strippers operatively associated with said punch and carried by said structure, each of said strippers being provided with a threaded 50 shank and an inturned end, said shanks being threaded into said structure in such manner as to permit the strippers to be rotated about axes paralleling that of said punch whereby to position the inturned ends of said 55 strippers in a common plane or in planes spaced from each other axially of said punch axis.
- 60 9. In a machine for punching sheet-form material, in combination, a punch supporting turret disposed to one side of the sheet plane and provided with a bore extending therethrough, a punch ram arranged for reciprocatory movement axially of said bore, the diameter of said ram being less than 65 the internal diameter of the turret bore, a plurality of split tubular bearing members arranged in longitudinal extension of each other and inserted between said ram and turret, and means effective to prevent displacement of said bearing members during the reciprocatory movement of said ram. 70
10. In a machine for punching sheet-form material, in combination, a punch supporting turret disposed to one side of the sheet plane and provided with a bore extending therethrough, the lower portion of which is of decreasing diameter, a punch ram arranged for reciprocatory movement axially of said bore, a bearing member having a cylindrical internal surface and a tapered external surface received within said lower portion of the turret bore in embracing relation with respect to said ram, and wedging means accommodated within the upper portion of said bore for maintaining said bearing member in position against longitudinal displacement. 75
11. In a machine for cutting sheet-form material, in combination, a die located at one side of the sheet plane, a reciprocatory punch located at the opposite side of said sheet plane a spring-pressed feed-limiting member movable through the die opening in unison with said punch, and means for maintaining the proximate ends of said punch and feed-limiting member a constant predetermined distance apart during the operation of the machine. 80
12. In a machine for cutting sheet-form material, in combination, a die located to one side of the sheet plane, a reciprocatory punch located to the opposite side of said sheet plane, a feed-limiting member movable through the die opening, means for maintaining the proximate ends of said punch and feed-limiting member a predetermined distance apart, and means permitting said feed-limiting member to be deflected toward one edge of said die opening. 85
13. In a machine for cutting sheet-form material, in combination, a relatively fixed support for a turret, a turret rotatably mounted within said support, said turret being provided with a die receiving seat, a die adapted for positional adjustment within said seat, and means for securing said turret in radially adjusted position with respect to its support. 90
14. In a machine for cutting sheet-form material, in combination, a relatively fixed sleeve, a turret rotatably disposed within said sleeve, said turret being radially shiftable within said sleeve, means for securing said turret in radially adjusted position with respect to said sleeve, and a punch tool carried by said turret. 95
15. In a machine for cutting sheet-form material, in combination, a turret located to one side of the sheet plane, a punch operatively associated with said turret, a ram ex- 100

tending vertically through said turret for supporting and imparting motion to said punch, a reciprocable cross-head for said ram, and means interconnecting said ram and cross-head for precluding rotation of said ram about the axis thereof.

16. In a machine for punching sheet-form material, in combination, a die located at one side of the sheet plane, a reciprocatory punch located at the other side of said plane and in alignment with the die, a feed limiting member reciprocable through the die opening and operable in synchronism with said punch, said member being shiftable out of axial alignment with respect to said die opening as said punch penetrates the sheet material, and means for maintaining said member in axial alignment with said die opening except when forced out of said alignment through the spreading action of the slug punched from the material.

17. In a machine for cutting sheet-form material, in combination, a die located at one side of the sheet plane, a reciprocatory punch located at the opposite side of said plane and adapted to register with said die, a feed limiting member adapted to move centrally through said die from one side of said sheet plane to the other side thereof, said member being normally out of contact with any portion of said die and being adapted to be forced out of axial alignment with respect to the die opening solely by a force approximating that exerted against the member by the slug being punched from the material.

18. In a machine for cutting sheet-form material, in combination, a die located at one side of the sheet plane, a reciprocatory punch located at the opposite side of said plane and adapted to coat with said die to punch slugs from said material, a feed limiting member movable through said die from one side of said sheet plane to the other side thereof, said member being shiftable laterally with respect to the die opening solely by a pressure approximating that caused by the slugs punched from said material, and means insuring synchronous operation of said feed limiting member with respect to said punch.

19. In a machine for cutting sheet-form material, in combination, a die located at one side of the sheet plane and having an opening of predetermined cross-sectional area, a reciprocatory punch located at the opposite side of said sheet plane with the axis thereof in coincidence with that of said die opening, and a feed-limiting member movable through said die opening and in unison with said punch, said member being of a cross-sectional area less than that of said die opening and being adapted to be forced into axial misalignment with respect to said die opening by the spreading action of the slug produced by the impact force of the punch and not by the normal feeding pressure of the sheet thereagainst.

20. In a machine for cutting sheet-form material, in combination, a die located at one side of the sheet plane, a reciprocatory punch located at the opposite side of said sheet plane and in alignment with said die, and a spring-pressed feed-limiting member movable through the die opening in unison with said punch throughout the entire stroke of the latter, said member being normally maintained in coaxial alignment with said punch and incapable of being forced out of said alignment except by a pressure approximating that exerted thereagainst by the slugs punched from said material.

21. In a machine for cutting sheet-form material, in combination, a die located at one side of the sheet plane, a reciprocatory punch located at the opposite side of said sheet plane and coaxial with said die, a feed-limiting member reciprocable through said die and across said plane in unison with said punch, and manually operable means for withdrawing said member from said sheet plane independently of said punch, said member being shiftable out of axial alignment with the punch only by a lateral force approximating that exerted by a slug being punched out of said material.

In testimony whereof, I have hereunto affixed my signature.

CHARLES B. GRAY.
